(57) **CLAIM**

We claim the ornamental design for a segmented electroplating
anode and anode segment, as shown and described.

DESCRIPTION

FIG. 1 is a top perspective view of a segmented electroplating
anode and anode segment showing our new design;

FIG. 2 is a bottom perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a top perspective view shown in environmental use;
and,

FIG. 8 is a bottom perspective view shown in environmental
use.

The broken lines shown represent unclaimed subject matter
and form no part of the claimed design.
